CLAIM

(21) Appl. No.: **29/415,301**

The ornamental design for an operation panel for an image forming apparatus, as shown and described.

(22) Filed: **Mar. 9, 2012**

DESCRIPTION

(30) **Foreign Application Priority Data**

Dec. 6, 2011 (JP) 2011-028220

FIG. 1 is a front view of an operation panel for an image forming apparatus, showing the new design;

(51) **LOC (9) Cl.** **16-03**

FIG. 2 is a rear view thereof;

(52) **U.S. Cl.**

FIG. 3 is a right-side view thereof;

USPC **D18/41**

FIG. 4 is a left-side view thereof;

(58) **Field of Classification Search**

FIG. 5 is a top view thereof;

USPC D18/36-41, 44-56; 222/DIG. 1; 271/3.14,
271/8.1, 226, 278; 355/97, 99; 358/1.1;

399/365, 367, 381-383, 388

FIG. 6 is a bottom view thereof;

See application file for complete search history.

FIG. 7 is a front, left side and top view thereof;

(56) **References Cited**

FIG. 8 is a front, right side and top view thereof; and,

U.S. PATENT DOCUMENTS

FIG. 9 is another front, left side and top view thereof, showing

D352,522 S * 11/1994 Tomatsu et al. D18/40
D537,471 S * 2/2007 Inoue D18/41
D556,821 S * 12/2007 Horiguchi et al. D18/41
D577,763 S * 9/2008 Hidaka et al. D18/39

the operation panel attached to an image forming apparatus.

In operation, the operation panel is attached to an image forming apparatus such as a copying machine, a printer, a facsimile machine, a scanner, a combination of such machines, or the like. A user may use the operation panel to operate each function of the image forming apparatus, such as copying, printing and scanning.

The broken line showing of the operation panel is for the purpose of illustrating environmental structure and forms no part of the claimed design. Subject matter shown in broken lines in the drawings forms no part of the claimed design.
